UNITED STATES PATENT OFFICE.

LEWIS H. JOHNSON, OF MADISON, AND ALFRED E. HAGUE, OF WEST ORANGE, NEW JERSEY, ASSIGNORS TO BELL TELEPHONE LABORATORIES, INCORPORATED, OF NEW YORK, N. Y., A CORPORATION OF NEW YORK.

CALL-CHARGING TELEPHONE-EXCHANGE SYSTEM.

Application filed October 20, 1927. Serial No. 227,396.

This invention relates to a telephone exchange system and more particularly to a system in which a charge is automatically made for a completed call. The object of the invention is the provision of means for controlling the call charging, which will charge the calling subscriber in such a manner as to more equitably recompense the operating telephone company for the use of exchange equipment.

In large exchange areas having several offices, some of which may be located at varying distant points in the area, it is desirable that means be provided whereby calling subscribers may be charged differently for calls to offices which are most remotely located from the office in which the calling line terminates, than for calls to offices which are not so remotely located, since remotely located offices must be reached over long interoffice trunks which are expensive to install and maintain and it is not equitable to the operating company to provide service to all points in the exchange area at the same basic rate.

Of course, where calls are handled on a manual basis the rate of charge may be very easily cared for by the operator who is able to require the calling subscriber to deposit the required number of coins in his coin-box before giving him a desired connection or to cause the proper operation of the subscriber's message register. However, where connections are established entirely by machine switching means some provision must be made for automatically controlling the charging of the call in accordance with the zone of the exchange into which the call has been extended by the calling subscriber.

Furthermore, it is not equitable to the operating company that for a basic charge a subscriber shall be enabled to hold an established connection indefinitely. In manual systems, of course, the operator is able to assess the charge in accordance with the number of unit periods during which conversation is continued on any call. Where, however, calls are extended by means of machine switching devices, operator supervision is not desirable and from a standpoint of economy the supervision of elapsed time should be attained by automatic means.

Both automatic charging in accordance with the zone of the exchange area into which

a call is extended and in accordance with the elapsed conversational period has heretofore been accomplished. In accordance with the present invention, however, one specific embodiment of which is disclosed herein by way of illustration, this is accomplished in the following improved manner:

A timing switch is provided which is started upon the response of the called subscriber and under the control of a timing interrupter completes its cycle once during each unit period of conversation, the unit period having been chosen as that which would be proper for a single unit charge, for example five minutes. The timing switch advances a recording switch to a position which is indicative of the number of such periods lapsing during the conversation, the number of steps taken by the recording switch during each cycle of the timing switch or during each unit period of conversation, being determined by the zone into which the call has been extended. The number of steps which the recording switch shall take for each unit period is controlled by the sequence switch of the district selector with which the charge controlling equipment is associated and by the sender, the sequence switch assuming different positions dependent on the zone into which the call is extended by the district selector. Upon the termination of the call the timing switch is set into a position which is complementary to that assumed by the recording switch and is then restored, sending impulses for operating the subscriber's message register to charge the call. Registration is thus effected in accordance with both the elapsed time for the terminated conversation and in accordance with the zone of the exchange into which the call was extended.

Where subscribers' lines are used having two-party substations thereon, it is desirable to prevent a subscriber on the line from interfering with the registration of a call through the initiation of a new call. For this purpose provision is made for shunting the line relay during the operation of one of the two message registers associated with the line.

A clearer conception of the scope and purpose of the invention will be obtained from a consideration of the following description, taken in connection with the attached drawings, in which:

Fig. 1 shows a calling subscriber's line having two substations thereon, together with certain relays for preventing interference between calling lines;

5 Fig. 2 shows a start circuit and a portion of two link circuits;

Fig. 3 shows a line finder;

Fig. 4 shows a link circuit for associating the sender of Fig. 5 with the district selector of Fig. 7;

10 Fig. 5 shows a portion of a register sender;

Fig. 6 shows a call charging control circuit;

15 Fig. 7 shows a district selector;

Fig. 8 shows in schematic form selectors for completing connections to an automatic subscriber, to a manual office or to an operator; and

20 Fig. 9 shows the manner in which Figs. 1 to 8 should be arranged.

The invention has been embodied in a disclosure which is substantially like that of Patent 1,567,072 to W. H. Matthies, granted December 29, 1925. Both the present disclosure and that of the Matthies patent show a skeletonized sender substantially identical with that employed in the more complete disclosure of Patent 1,589,402, to O. H. Kopp, granted June 22, 1926. Reference to the Kopp patent is made for operations not completely described herein.

As in the case of the above mentioned patents, a plurality of link circuits are arranged 25 to serve a group of calling lines and are taken into service in rotation. When a link circuit completes its function it hunts for and associates itself with a district selector which is ready for use and the link and district relay 40 main in a sub-allotted condition until the next link in the series has been put into service. The link circuit is then put into an allotted condition, from which it will be advanced by the initiation of a call and the 45 action of the start circuit of Fig. 2. The trip circuit of Fig. 1 and the start circuit of Fig. 2 are so arranged that only one line may be served at a time and so that there may be cooperation between two groups of lines, to 50 each of which a group of link circuits is individual. The details of these functions are described in the above mentioned Matthies patent and since they form no part of the present invention will be omitted from the 55 following description.

Establishment of connection.

It will first be assumed that the subscriber at substation 100 removes his receiver from 60 the switchhook to initiate a call, thereby closing a circuit from battery through the winding of line relay 101, inner left contact of relay 102 over the subscriber's line to ground at the outer left contact of relay 102. Relay 65 101 in operating closes a circuit from battery

through resistance 104, winding of relay 103 to ground at the outer front contact of relay 101. It also prepares a circuit from battery through resistance 111 and the right winding of relay 109 in parallel, inner front contact of relay 101 to conductor 114, to identify the calling line to the line finder. Relay 103 in operating closes a circuit from battery, over the left back contact of relay 201, conductor 130, right winding of relay 108, inner left contact of relay 107, inner right contact of relay 103 to ground at the left contact of relay 109.

70 Relay 108 operates in this circuit and closes a locking circuit for itself from battery through the right winding of relay 201, conductor 129 over back contacts of relays similar to relay 108 individual to other groups of lines appearing before the same line finder, inner left front contact and left winding of relay 108 to ground at the right contact of relay 109. Relay 108 prepares a circuit from ground at its outer right contact through the winding of trip magnet 303 of the line finder to battery in preparation for tripping the proper set of brushes when the line finder is 80 operated. Relay 201 operates in the locking circuit of relay 108 and in combination therewith closes a circuit from ground over its outer right contact, conductor 128, inner 85 right contact of relay 108, winding of relay 110 to battery. Relay 110 locks over its inner right contact to ground at the left contact of relay 109. Relay 110 closes a circuit for starting the allotted line finder. Assuming 90 that the link and line finder shown are the ones to be used next, sequence switch 400 will be standing in position 1 and sequence switch 700 in position 2. The operation of relay 110 will therefore close a circuit from 95 ground at its outer contact, outer left contact of relay 108, inner left contact of relay 103, conductor 131, left back contact of relay 202, inner left back contact of relay 203, conductor 206, upper left and lower right contacts 100 of cam 403, brush 402 and terminal 401, conductor 701, left contacts of cam 702, conductor 703, brush 602 and normal bank terminal of recording switch 600, outer right back contact of relay 607, conductor 608, winding of 105 relay 302 to battery. 110

115 Relay 302 in operating closes a circuit from battery through the winding of up-drive magnet 304 of the line finder, outer left contact of relay 302, lower right contact of cam 704, outer right front contact of relay 302, upper left contact of cam 705 to ground. The line finder moves upward under the control of magnet 304 and since the trip magnet 303 is operated the proper set of brushes is 120 tripped. As soon as the line finder moves upward a locking circuit is provided for relay 302 extending over its inner left contact, lower contacts of cam 706, right back contact of relay 320, commutator strip 321, brush 322 125 130

to ground, which holds relay 302 operated independent of the start circuit. At its inner right front contact relay 302 establishes a circuit for relay 300, extending from battery 5 through the left winding of relay 300, inner right contact of relay 302, lower right contact of cam 704 to ground, as previously traced at the upper left contact of cam 705. As soon as commutator brush 307 engages 10 segment 305, a circuit is closed from ground, over brush 307 and segment 305, the innermost left contact of relay 300, conductor 404, contact 230 of key 204, inner right front contact of relay 201 to conductor 129 and the 15 right winding of relay 201. This circuit shunts the winding of relay 108 and causes that relay to release, in turn releasing the trip magnet 303. When brush 307 leaves segment 305, the circuit of relay 201 is 20 opened and that relay also releases.

When line finder brush 381 makes contact with terminal 380, which is connected to conductor 114 and therefore to battery, a circuit is completed from this battery through the 25 winding of relay 320, inner left back contact of relay 707, upper right and lower left contacts of cam 708 to ground. Relay 320 operates in this circuit and closes a shunt around its winding through resistance 319 to 30 ground over commutator strip 321 and brush 322. This reduces the resistance in series with the winding of marginal relay 109 sufficiently to cause that relay to operate and to open the locking circuit of relay 110, which 35 in turn opens the energizing circuit of relay 302. The operation of relay 320 also opens the locking circuit of relay 302, causing that relay to release. The release of relay 302 opens the circuit of the up-drive magnet 304 40 to arrest the hunting movement of the line finder and opens the circuit of relay 300, which also releases. The release of relay 300 closes a circuit from ground through the winding of cut-off relay 102, conductor 112, terminal 327, brush 326, innermost lower back contact of relay 317, right contacts of cam 709, right back contact of relay 300, resistance 323 to battery. The operation of cut-off relay 102 opens the circuit of line relay 101, removing battery from conductor 114, thus releasing relays 109 and 320.

At the time relay 300 operates it closes a circuit from ground at its middle left contact over the inner right back contact of relay 301, conductor 379, terminal 407 and brush 406 of the link district finder 410, lower right contact of cam 408, winding of relay 409, resistance 411 to battery. Relay 409 operates and closes a circuit from battery 45 through the winding of sequence switch magnet 400, upper contact of cam 412 to ground at the outer left front contact of relay 409, advancing the link sequence switch 400 to position 2. When sequence switch 400 50 leaves position 1, relay 409 is released. In

position 2 a circuit is closed from battery through the winding of relay 413, upper contacts of cam 414, right back contact of relay 415 to ground at the left contact of cam 416. Relay 413 operates, closing a circuit from battery 70 through the left winding of relay 417, left front contact of relay 413 to ground at the left back contact of relay 415. Relay 417 upon operating closes a circuit from battery through the winding of up-drive magnet 418 of the sender finder 420, left contact of cam 479, outer right contact of relay 417 to ground at the left back contact of relay 409. The sender finder moves upward under control of magnet 418 in search of an 80 idle sender.

Relay 413 also closes a circuit from battery through the right winding of relay 415, upper contacts of cam 421, middle winding of relay 415 to ground at the right contact 85 of relay 413. The current in this circuit, however, is not sufficient to operate relay 415, but does create a flux in the windings of that relay so that it becomes quick to operate when the test circuit is closed. The 90 test circuit extends from brush 422 over the lower contacts of cam 419, right back contact of relay 409, left winding of relay 415, lower right and upper left contacts of cam 421, middle winding of relay 415 to ground 95 at the right contact of relay 413. An idle sender is characterized by battery connected to conductor 502. When, therefore, brush 422 engages terminal 423, corresponding to the sender of Fig. 5 which is assumed to 100 be idle, the test circuit above traced is completed over terminal 423 to battery, and relay 415 operates quickly. The relay 415 upon operating closes a locking circuit for itself from battery through its right winding, upper contacts of cam 421 to ground at its left front contact. It also opens the circuit of relay 417, which releases, in turn releasing magnet 418 and bringing the sender finder to rest on the terminals of the idle 110 sender. The release of relay 417 in turn releases relay 413. When relay 413 releases with relay 415 operated, a circuit is closed from battery through the winding of sequence switch magnet 400, lower left contact of cam 476, contact 427 of jack 428, left back contact of relay 413, right front contact of relay 415 to ground at the left contact of cam 416, advancing sequence 115 switch 400 to position 3.

When sequence switch 400 reaches position 3, a circuit is closed from ground through the left and middle windings of relay 503, left back contacts of relays 504 and 505, conductor 506, terminal 430, brush 431, right contact of cam 434, brush 432 and terminal 433, conductor 315, contacts of cam 710 (assuming that the district selector has been advanced to position 3, as hereinafter described), through the lower wind- 120 125 130

ing of relay 317 and the winding of relay 351 in parallel to battery. Relay 317 is marginal and does not operate, but relay 351 operates, although ineffective at this time.

5 Relay 503 also operates and closes an obvious circuit for relay 507, which in turn closes a circuit for relay 509. Relay 509 closes a circuit for relay 510.

As soon as sequence switch 400 arrived 10 in position 2 1/4 it prepared the pulsing circuit for receiving dial pulses. This circuit may be traced from battery through the left winding of relay 500, conductor 537, terminal 440, brush 441, lower contact of cam 429, brush 478, terminal 477, conductor 375, lower right contact of cam 711, upper back contact of relay 317, upper back contact of relay 306, brush 334, terminal 333, conductor 117 through the subscriber's substation, conductor 20 116, terminal 332, brush 331, lower back contact of relay 306, lower back contact of relay 317, winding of relay 330, upper right contact of cam 712, conductor 382, terminal 442, brush 443, upper right and lower left contacts of cam 403, brush 444 and terminal 445, to ground at the back contact of relay 513. Relay 500 operates, in turn operating relay 518 in the well known manner, relay 518 operating relay 519. A circuit is therefore 30 closed from the source of tone 516, through the right winding of relay 500, register steering switch brush 520 in its normal position, front contact of relay 519, contact of cam 514 to ground at the outer right front contact of relay 509. This tone is transmitted to the calling subscriber to inform him that the sender is ready to receive impulses which he may then send out by manipulating his dial. When relay 510 operated 40 it removed battery from conductor 502, releasing relay 415. When relay 415 releases, a circuit is closed from battery through the winding of sequence switch magnet 400, upper left contact of cam 476, right back contact of relay 415 to ground at the left contact of cam 416. Sequence switch 400 advances to position 5 over this circuit and remains in this position throughout the further operation of the sender.

50 The calling subscriber now proceeds to dial the desired line number for setting the registers and translator (not shown) of the sender in the well known manner. After the dialing of the first digit the register steering switch, one wiper of which is shown at 520, advances from normal, closing a circuit for relay 517, extending from battery through the winding of relay 517, terminals and brush 520, contact of relay 519, contact of cam 514 to ground at the outer right contact of relay 509. Relay 517 closes an obvious circuit for relay 521.

As soon as the code registers of the sender 60 have been set in accordance with the first two digits dialed by the calling subscriber,

the translator is set in the manner described in the aforementioned patent to O. H. Kopp. When the translator assumes its setting relay 533 operates, closing a circuit over the translator arc 534 through a back contact of relay 535, if the subscriber has dialed the number of a subscriber located in a zone of the exchange for which an additional charge must be made on the calling subscriber's message register, thence through the winding of relay 536 to battery. Relay 536 energizes and locks over its left front contact, the contact of cam 514 to ground at the outer right front contact of relay 509, and extends locking ground through its left front contact to the winding of relay 538, causing the operation of the latter relay. Relay 538 upon operating establishes a circuit from ground at the outer right contact of relay 509, the contact of cam 514, the contact of relay 538 to battery through the winding of relay 535. Relay 535 operates, opening the initial energizing circuit of relay 536 and connecting the translator arc 534 over the cable 539 to the class switch 540 which is diagrammatically indicated in the upper right portion of Fig. 5. The class switch is thereupon set from the arc 534 of the translator in the well known manner. Relay 536 upon energizing prepares a circuit extending from ground over its right contact, the contacts of cams 571 and 542, closed during the brush selection controlling positions of the sequence switches associated with the sender, conductor 543, terminal 439, brush 438, right contacts of cam 405, brush 406, terminal 407, conductor 379, the inner right back contact of relay 301 to the upper right contact of cam 770. This circuit is completed as will be described hereinafter through the winding of relay 611 of the registration controlling circuit for indicating at the registration controlling circuit the fact that the subscriber has initiated the establishment of a connection into a zone of the exchange area for which he should be assessed an additional charge.

When the link circuit advances into position 2 for hunting for an idle sender, a circuit is closed for relay 714 extending from battery through the left winding of relay 714, lower right contact of cam 715, upper left contact of cam 716, conductor 375, terminal 477 and brush 478 of district finder 410 to ground at the right contact of cam 429. When relay 302 releases and relay 714 energizes, a circuit is closed for advancing sequence switch 700 into position 3, extending from battery through magnet 700, the lower left contact of cam 717, outer left front contact of relay 714, right back contact of relay 302 to ground at the upper left contact of cam 705. As the sequence switch 700 advances from position 2 to 3, relay 714 releases.

When sequence switch 700 is in position 3

a circuit is closed to test the responsive condition of relay 308. This circuit extends from battery through the winding of relay 308, the right winding of relay 309 to ground 5 through the left contacts of cam 708. The current flow through the winding of relay 308 at this time is the least upon which this relay should operate. If relay 308 operates, as it should, a circuit is closed for relay 310, 10 extending from battery through the winding of relay 310, outer left back contact of relay 311 to ground at the contact of relay 308. Relay 310 locks over its inner right front contact to ground at the lower left 15 contact of cam 727 and prepares a circuit for advancing sequence switch 700 into position 4. With sequence switch 700 in position 3, relay 714 is again energized over a circuit extending from battery through its left winding, the lower right contact of cam 715, the 20 lower left contact of cam 716, conductor 701, terminal 401 and brush 402 of district finder 410, the lower right and upper left contacts of cam 435, brush 436 and terminal 437 of 25 sender finder 420, conductor 532, the front contact of relay 521, the right back contact of relay 504, the left contact of cam 526, winding of sender stepping relay 522, winding of overflow relay 523, left contact of 30 cam 527, resistance 530 to ground. Relays 522 and 714 operate in this circuit, relay 714 locking over its inner left front contact and the lower left contact of cam 715, thence over the circuit traced whereby it remains energized as the sequence switch 700 advances into 35 position 4. Relay 714 also closes a circuit to advance sequence switch 700 into position 4, extending from battery through magnet 700, upper left contact of cam 718, lower left 40 contact of cam 704, outer right contact of relay 310, outer left front contact of relay 714, right back contact of relay 302 to ground at the upper left contact of cam 705. As soon as sequence switch 700 leaves position 3, relays 308 and 310 release. 45

winding of this relay, the left contact of cam 719 to ground at the contact of relay 351, advancing the sequence switch 700 into position 10. In position 10 relay 714 remains energized over the circuit just traced. In position 10, which is the selection beyond position 70 of the district circuit, the control of succeeding switches is effected over a fundamental circuit which may be traced in part through the upper right and lower left contacts of cam 768, outer right back contact of relay 301, conductor 701, thence as traced to the sender, 75 through relays 522 and 523, cam 546, brush 544, compensating resistance 545, left back contact of relay 524, right front contact of relay 507, conductor 543, returning over terminal 439 and brush 438, the right contacts of cam 405, brush 406 and terminal 407, conductor 379, the inner right back contact of relay 301 to the right contacts of cam 770. 80

As soon as selections are completed and the connection has been set up to the called subscriber's line, reversed battery from the incoming selector operates relays 522 and 523 in the usual manner. These relays in turn cause the operation of relay 531 and relays 524 and 504. With these relays operated, the sender is advanced to position 18 for controlling talking selection. Relay 351 is operated in parallel with the winding of relay 317 85 throughout selections. The operation of relay 504 above mentioned now opens a shunt around the right winding of relay 503, including that winding in the circuit of relays 351 and 317. Relay 351 thereupon releases, in turn opening the circuit of relay 714, which 90 also releases. Upon the release of relay 714 the district sequence switch 700 is advanced into position 12 over a circuit extending from battery, winding of magnet 700, lower left contact of cam 713, outer left back contact of relay 714, outer right back contact of relay 302 to ground at the upper left contact of cam 705. As the sequence switch enters position 100 11, ground is connected to conductor 815.

When the district sequence switch reaches position 4 for controlling brush selection, the circuit previously prepared at the contact of relay 536 and extending to the upper right contact of cam 770 is completed over the upper left contact of cam 770, conductor 741, the outer right back contact of relay 609 to battery through the right winding of relay 611. Relay 611 upon energizing locks over its left winding and left contact, conductor 612 to ground at the upper left contact of cam 727.

11, ground is connected to conductor 315 at the lower right contact of cam 720, which is extended over terminal 433, brush 432, upper contacts of cam 446, left winding of relay 415, right back contact of relay 409, left contact of cam 434, brush 431, terminal 430, conductor 506, left back contact of relay 505 to the windings of relay 503. Since these windings are also connected to ground, relay 503 now releases, in turn releasing relay 507. The release of relay 507 does not release relay 509, since that relay is locked to its own front contact. A circuit is therefore closed from

The district selector is now controlled by the sender in its brush and group selections and then proceeds to hunt for an idle trunk in the well known manner. After an idle trunk is selected, a circuit is established in position 9 of the sequence switch 700 for relay 714, extending from battery through the right contact. A circuit is therefore closed from ground over the left back contact of relay 507, front contact of relay 509 to the winding of relay 505, which relay locks over its middle left contact to conductor 506 and to ground as above traced. After leaving position 11, relays 351 and 317 are both disconnected from conductor 315. After leaving

position 10, the subscriber's line becomes disconnected from the sender at contacts of cams 711 and 712.

5 *Test for particular calling substation.*

In positions 11 and 12 of sequence switch 700 a test of the calling line is made by the relay 308 to determine which party on the line has initiated the call. As the sequence 10 switch passes through positions 10 $\frac{3}{4}$ to 11 $\frac{1}{4}$ a circuit is established for relay 306 extending from battery, lower winding of relay 306, inner left back contact of relay 311, upper contacts of cam 721, commutator segment 15 312, brush 313 to ground. Relay 306 upon operating extends its own operating ground over its lower front contact to battery through the left winding of relay 309, energizing the latter relay. Relay 309 upon 20 energizing locks both itself and relay 306 over its inner left front contact, the left normal contacts of relay 314, the left normal contacts of relay 302, the right contacts of cam 706 to ground over commutator segment 312 25 and brush 313. Relay 309 at its outer right front contact also closes a secondary holding circuit for relay 306 through its upper winding. Relay 309 also connects the winding of relay 308 to brush 331 of the line finder 30 through the inner right contact of relay 309, and to brush 334 over the outer left contact of relay 309. Since the substation 100 has been assumed to be calling, these circuits will 35 be completed to ground over terminal 332, conductor 116, through the ringer at substation 100 and over terminal 333, conductor 117, switchhook contacts thence to ground through the ringer, and relay 308 will energize in turn operating relay 310, the latter relay locking to 40 ground at the lower left contact of cam 727.

Relay 306 also closes a circuit for relay 722, extending from battery through the right winding of relay 722, the lower contact of interrupter 723, conductor 724, the inner upper front contact of relay 306, conductor 725 to ground at the lower right contact of cam 705. Relay 722 locks independently of interrupter 723 over its inner right contact to the circuit above traced. When relay 722 45 energizes, as soon as interrupter 723 makes its upper contact a circuit is closed through the winding of relay 302, the outer right contact of relay 722, the upper contact of interrupter 723, conductor 724, innermost upper 50 front contact of relay 306, conductor 725 to ground at the lower right contact of cam 705. Relay 302 upon energizing opens the holding circuit of relay 309, which releases, in turn releasing relays 306, 722 and 302. 55 The timing interrupter 723 is so arranged that relays 306, 309 and 722 do not release until relay 308 has had time to operate and to lock relay 310 energized.

60 The release of relay 306 now connects the left windings of repeating coil 760 to the sub-

scriber's line, the calling subscriber being supplied with talking current over the following path: battery, lower left winding of coil 760, lower right contact of cam 712, winding of supervisory relay 330, lower back contacts of relays 317 and 306, brush 331, terminal 332, conductor 116 through the substation set 100, returning over conductor 117, terminal 333 and brush 334, upper back contacts of relays 306 and 317, upper right contact of cam 711 to ground through the upper left winding of repeating coil 760. Relay 330 operates in this circuit and closes a circuit for relay 707, extending from battery through the winding of relay 707, contact 80 of relay 330, upper contacts of cam 726 to ground at the upper right contact of cam 727.

70 *Talking selection.*

With sequence switch 700 in position 12, relay 714 is energized in a circuit extending to the sender from battery through its left winding, the lower right contact of cam 715, the lower left contact of cam 716, conductor 701, terminal 401, brush 402, the lower right and upper left contacts of cam 435, brush 436, terminal 437, conductor 532, the front contact of relay 521, the front contact of relay 504, the right contact of cam 526, the sender sequence switch being in position 18 for talking selection, the windings of relays 522 and 523, the right contact of cam 527 to ground through resistance 530. Relays 714 and 522 energize in this circuit, relay 714 closing a circuit extending from battery through sequence switch magnet 700, the lower left contact of cam 717, the outer left front contact of relay 714, the right back contact of relay 309 to ground at the upper right contact of cam 705. Relay 714 upon energizing locks to the fundamental circuit over its inner left front contact and the lower left contact of cam 715. As sequence switch 700 rotates out of position 12 toward position 16 ground is intermittently connected to the fundamental circuit in shunt of sender stepping relay 522 at the lower contacts of cam 708. When the sender is satisfied as to its talking selection setting, the fundamental circuit is opened at the sender through the operation of relay 525, and relay 714 de-energizes, arresting sequence switch 700 in its next stopping position. The sequence switch may be arrested in any one of three positions; position 13 which may be a no-charge position, and a charging position for connections to certain zones of the exchange, position 14 which is a charging position for connections to certain other zones of the exchange, and position 15 for connections to an operator's position.

115 At the sender after talking selection is completed, relay 515 operates connecting battery to conductor 506 in parallel with the winding of relay 505. The current in this 120 circuit is now sufficient to operate relay 415 125

which closes a circuit from battery through the left winding of relay 417, left contacts of cam 421, to ground at the left front contact of relay 415. Relay 417 closes a circuit from 5 battery through the winding of sequence switch magnet 400, upper contact of cam 479, outer right front contact of relay 417, left back contact of relay 409 to ground, advancing sequence switch 400 to position 6. In 10 this position, all of the conductors extending to the sender are opened and the sender is completely released. As soon as sequence switch 400 leaves position 5, relay 415 releases and in turn releases relay 417 unless 15 the sender finder 420 is standing on one of its top ten terminals. If the latter is true, relay 417 is held operated in a circuit from battery over its left winding, left front contact, upper left contact of cam 424, commutator segment 464, brush 463 to ground. With relay 417 operated at this time, a circuit is closed from battery through resistance 411, winding of relay 409, lower contacts of cam 414, inner right front contact of relay 25 417, lower left contact of cam 416 to ground. Relay 409 locks through its inner left contacts to ground at the lower contact of cam 467 and also closes a second locking circuit for relay 417. With relay 409 operated, a 30 circuit is closed from battery through the winding of down-drive magnet 465 of the sender finder 420, left contact of cam 412, to ground at the outer left front contact of relay 409. When the sender finder reaches its low- 35 ermost position, a circuit is closed from ground over brush 463, bottom commutator segment 406, upper contact of cam 456 to resistance 411, shunting the winding of relay 409 and causing that relay to release and in 40 turn release relay 417. With relay 417 released in position 6, a circuit is closed from battery through the winding of sequence switch magnet 400, lower right contact of cam 476, right back contact of relay 417, to ground at the lower left contact of cam 416, advancing sequence switch 400 to position 7. 45 When sequence switch 400 reaches position 7, the link circuit is ready to associate itself with another district. If another district 50 is standing in position 1 waiting association with a link, a circuit will be closed from ground over the lower left contact of cam 708 and lower right contact of cam 728 of that district, contact 393 of jack 374, conductor 392, contact of jack 448, contact of jack 449, upper contact of cam 416, right back contact of relay 415, upper contacts of cam 414, winding of relay 413 to battery. Relay 413 closes a circuit from battery 55 through the left winding of relay 417, left front contact of relay 413, to ground at the left back contact of relay 415. Relay 417, in operating, closes a circuit for up-drive magnet 447 of the district finder 410, lower right contact of cam 479, right front contact of 60 relay 417, left back contact of relay 409, to ground. The district finder moves upward under control of magnet 447 in search of the district which is awaiting a link. Such a district is identified by battery connected 70 over the left contacts of cam 709 of that district, contact 373 of jack 374, to conductor 366. Relay 413, in operating, closes the same circuit through the right and middle windings of relay 415 as it closed in position 2. 75 At this time the test circuit extends from ground at the right front contact of relay 413, through the middle winding of relay 415, upper left and lower right contacts of cam 421, left winding of relay 415, right 80 back contact of relay 409, lower right and upper left contacts of cam 419, contact of jack 449 to brush 451. 85 If the district for which the district finder is hunting does not lie between the last position occupied by the finder and the top of its bank, it will continue to move upward until brush 453 engages segment 452, completing a circuit over the upper right contact of cam 408, winding of relay 409, resistance 411 to 90 battery. The operation of relay 409 opens the test circuit, opens the circuit of up-drive magnet 447 and closes a circuit from battery through the winding of down-drive magnet 454, lower right contact of cam 412, left front contact of relay 409 to ground. The district finder is restored to its lowermost position under the control of magnet 454, at which time a circuit is closed from ground over brush 453, bottom segment 455 of the district 95 finder commutator, lower right contact of cam 456 to resistance 411, shunting and releasing relay 409 which restores the test circuit and the circuit of up-drive magnet 447. 100 When brush 451 encounters terminal 450 to 105 which conductor 366 extends, the test circuit is completed and relay 415 operates quickly. As in the previous case, relay 415 locks through its right winding, the upper contacts of cam 421, to ground at its left front 110 contact, opening the circuit of relay 417 to de-energize magnet 447 and to bring the district finder to rest on the terminals of the district. With relay 415 operated and relay 417 released, a circuit is closed from battery 115 through the winding of sequence switch magnet 400, lower left contact of cam 476, contact 427 of jack 428, back contact of relay 413, right front contact of relay 415, upper right contact of cam 416, contacts of jacks 449 120 and 448 to conductor 392. Sequence switch 400 advances to position 8 in this circuit. 125 Relay 415 is held operated in position 8 from battery at the district over terminal 450, brush 451, contact of jack 449, upper left and lower right contacts of cam 419, back contact of relay 409, left winding of relay 415, lower right and upper left contacts of cam 421, to ground at the left front contact of relay 415. With relay 415 operated, a cir- 130

circuit is closed from ground at the left contact of cam 416, right front contact of relay 415, upper left contact of cam 429, brush 478, terminal 477, conductor 375, upper left contact 5 tact of cam 716, lower right contact of cam 715, left winding of relay 714 to battery. Relay 714 operates and closes a circuit from battery through the winding of sequence switch 10 magnet 700, lower left contact of cam 717, outer left front contact of relay 714, outer right back contact of relay 302, to ground at the upper left contact of cam 705. Sequence switch 700 advances to position 2 in this circuit, releasing relay 714. The advance 15 to position 2 removes ground from conductor 392 and battery from conductor 366. The removal of battery from conductor 366 opens the circuit of relay 415, and that relay releases, closing a circuit from battery through 20 the winding of sequence switch magnet 400, upper left contact of cam 476, right back contact of relay 415, to ground at the lower left contact of cam 416. Sequence switch 400 advances to position 9. 25 The link circuit remains in this position until the link circuit standing next to it in the series is advanced from position 1 for the purpose of selecting a sender. Link circuit 260 occupying that relationship to the 30 link circuit of Fig. 4, a circuit may be traced from ground over the lower contact of cam 261, upper right contact of cam 262, conductor 263, contact 460 of jack 428, upper right contacts of cams 461 and 462, winding 35 of sequence switch magnet 400 to battery, advancing the link circuit to position 10 which is the equivalent of position 1, so that the link circuit is ready to operate in response to the next call in the group of lines served 40 thereby.

Charge calls initiated by substation 100.

It will first be assumed that the call which has been completed is of such a character 45 that a charge should be made for it. For this call to a remote zone of the exchange, therefore, the district sequence switch 700 has been set into position 14. With sequence switch 700 in position 14 a circuit is closed 50 for relay 609 extending from battery, winding of relay 609, conductor 610, to ground at the left contact of cam 720. When the called subscriber responds a circuit is completed for relay 729 extending from the tip brush 55 730, over the upper contacts of cam 768, the upper right winding of repeating coil 760, winding of relay 729, lower right winding of coil 760, lower contacts of cam 770, to the brush 731. Relay 729 energizes and a circuit 60 is established for relay 722 as soon as interrupter 732 closes its lower contact, from battery, through the left winding of relay 722, the lower contact of interrupter 732, the lower left and upper right contacts of cam 718, the 65 front contact of relay 729, conductor 733, to

ground at the inner right front contact of relay 609. A circuit is closed upon the energization of relay 722 extending from battery, winding of stepping magnet 657 and brush 655 and its first terminal of the timing switch 70 750, conductor 613, outer left contact of relay 722, upper contact of charging interrupter 732, lower left and upper right contacts of cam 718, front contact of relay 729, conductor 733, to ground at the inner right 75 front contact of relay 609. Under the control of interrupter 732 the timing switch is advanced into position 7.

As the timing switch passes through a position 2, a circuit is closed to advance the recording switch 600 one step. This circuit extends from battery, through the winding of stepping magnet 625, conductor 614, brush 605 and the first terminal of the bank associated therewith, inner left front contact of 80 relay 609, conductor 616, upper contacts of cam 719, closed in position 14, conductor 617, outer left front contact of relay 609, No. 2 terminal and brush 656 of the timing switch 85 90 95 650, outer right back contact of relay 615, to ground over the No. 2 terminal and brush 653 of the timing switch. When the timing switch passes through position 3 ground on brush 656 is connected to conductor 336 and thence to battery through the winding of charge relay 335 operating this relay. Relay 335 now locks over its inner right front contact to ground at the lower left contact of cam 720 and at its intermediate right contact extends its locking ground through the winding of relay 311, energizing the latter relay. Relays 311 and 335 perform no other useful 100 functions at this time.

As timing switch 650 passes through position 4, since the relay 611 has been assumed 105 to be operated, ground on brush 656 is extended through the right front contact of relay 611, brush 605 and its No. 2 terminal, to battery through the stepping magnet 625. The recording switch thereupon steps to its No. 3 110 position. When the timing switch 650 advances through position 6, ground on brush 656 is again extended over the right front contact of relay 611, brush 605 and its No. 3 bank terminal, conductor 614, to battery 115 through the stepping magnet 625. Thus while the timing switch is advancing into position 7 the recording switch is advanced three steps.

As soon as the timing switch reaches position 7, a circuit is established from battery, through its stepping magnet 657, brush 655, strapped terminals 7 to 22, conductor 618, outer right contact of relay 707, conductor 734, interrupter 619, conductor 620, upper contacts of cam 726, to ground at the upper right contact of cam 727. Under the influence of slow interrupter 619, the timing switch is now advanced around into normal 120 position, the time required for the complete 125 130

cycle of the timing switch being approximately five minutes. If conversation still continues, the above described operations of switches 600 and 650 continue throughout the duration of conversation, the recording switch 600 being advanced three steps for each complete cycle of switch 650.

When the calling subscriber hangs up to terminate the call, relay 330 deenergizes, opening the energizing circuit of relay 707. Relay 707 is, however, held energized over its inner right front contact, contact 736 of interrupter 735, the upper contacts of cam 726, to ground at the upper right contact of cam 727 until the interrupter opens the contact 736. With relay 707 released, the disconnect relay 317 energizes as soon as interrupter 735 again makes its contact 737, over a circuit extending from battery, lower winding of relay 317, upper contacts of cam 710, outer left back contact of relay 707, contacts 737 and 736 of interrupter 735, to ground over the upper contacts of cam 726 and the upper right contact of cam 727. The interrupter 735 in conjunction with relay 707 introduces a relay in the operation of relay 317 of approximately 0.25 seconds so that should the calling subscriber accidentally depress the switchhook, the connection will not be wiped out. The operation of relay 317 disconnects the tip and ring conductors of the subscriber's line from the repeating coil 760 and closes a circuit for advancing sequence switch 700 to position 16. This circuit may be traced from battery, winding of magnet 700, lower contacts of cam 721, innermost upper front contact of relay 317, to ground at the upper left contact of cam 727.

A test is now made to determine if the ground placed on the tip and ring conductors of the calling line at the substation 100 has been removed as it should be when the calling subscriber restores his receiver to the switchhook. With sequence switch 700 in position 16, a circuit is established from battery, lower winding of relay 306, inner left front contact of relay 311, lower right contact of cam 738, to ground at the lower left contact of cam 708. Relay 306 energizes extending its operating ground from cam 708 over its inner lower front contact to the left winding of relay 309 which relay operates. At its outer right front contact relay 309 closes an obvious holding circuit through the upper winding of relay 306 and its inner left contact, closes a locking circuit for both itself and relay 309, extending through the left normal contacts of relay 314 and the inner left normal contacts of relay 302, the right contacts of cam 706, to ground over commutator segment 312 and brush 313. Relay 309 closes a circuit for relay 707 extending from battery, through its winding, the next to outer right front contact of relay 309, the upper contacts of cam 706, to ground over

segment 312 and brush 313 as soon as the sequence switch 700 reaches position 16. Relay 309 at its inner left and right contacts also connects the winding of relay 308 to the tip and ring brushes 334 and 331 of the line 70 finder and thence to the tip and ring conductors of the calling line. Relay 308 should not operate at this time.

Relay 306 upon energizing connects ground from the lower right contact of cam 705, conductor 725, inner upper contact of relay 306, conductor 724, over the lower contact of interrupter 723, to battery through the right winding of relay 722. Relay 722 locks over its inner right contact to ground over the circuit just traced, independently of the contact of interrupter 723, and when the interrupter closes its upper contact extends the ground on conductor 724 over the outer right contact of relay 722 to battery, through the winding of relay 302. Relay 302 energizes opening the locking circuit of relays 309 and 306 which release in turn releasing relay 722. With relay 309 released, a circuit is closed to advance sequence switch 700 to position 17 extending from battery, winding of magnet 700, the lower left contact of cam 713, the outer left back contact of relay 714, the inner right back contact of relay 309, to ground at the upper right contact of cam 705. As the sequence switch enters position 16 $\frac{3}{4}$ the holding ground extending to the contact 328 of relay 317 is extended over the lower left contact of cam 742, the outer right front contact of relay 311, the intermediate right front contact of relay 310 to battery through the right winding of relay 300. Relay 300 upon energizing extends this operating ground over its right contact to battery, through the left winding of relay 301, causing relay 301 to energize. At its outer right back contact relay 300 disconnects battery through resistance 323 from the sleeve conductor 112 of the subscriber's line thereby releasing the cut-off relay 102 and at its outer right front contact connects the sleeve multiple of the calling line through the winding of relay 337 to ground at the upper left contact of cam 727 so that should a final selector test the multiples of the calling line at this time, the relay 337 will be operated to open the message registering circuit which, as will hereinafter be explained, extends through the back contacts of this relay. False registration is thus prevented. Relay 102 upon deenergizing connects the message register 105 assigned to the calling substation 100 over the right back contact of relay 102 and the inner right back contact of relay 101 to conductor 114.

When the sequence switch 700 left position 16, relay 707 released. With relay 301 operated, a circuit is now closed to operate relay 615 extending from battery, winding of relay 615, conductor 621, left front contact of relay 301, conductor 622, brush 602, conductor 703,

upper contacts of cam 702, upper contacts of cam 710, outer left back contact of relay 707, contacts of interrupter 735, upper contacts of cam 726, to ground at the upper right contact of cam 727. Relay 615 upon energizing locks over its outer left front contact and the front contact of relay 301 independent of contacts of interrupter 735 and establishes a stepping circuit for magnet 657 of the timing switch 10 extending from battery, winding of magnet 657, inner right back contact of relay 607, terminals and brush 651, interrupter contacts of magnet 657 to ground at the middle left contact of relay 615. Switch 650 advances until 15 it assumes a position which is complementary to the position into which the recording switch 600 was advanced during the conversational period.

It will be assumed that switch 600 is standing in position 7 having been advanced six 20 steps during two cycles of switch 650 or during a conversation which lasted ten minutes. When therefore, switch 650 reaches position 10 a circuit is closed from battery, through 25 magnet 657, brush 604, in position 7, conductor 626, brush 654, resistance 630, the inner left back contact of relay 623, to ground at the inner left contact of relay 615. This circuit holds the magnet 657 from further operation. 30 As soon as interrupter 624 closes its contact, brush 654 becomes connected through the right winding of relay 607, outer normal contacts of relay 623, interrupter contacts 624, outer right front contact of relay 615, to 35 ground at brush 653. Relay 607 energizes in this circuit and at its inner right back contact opens the stepping circuit of switch 650 to arrest the further advance of the switch and at its left contact establishes a locking circuit for 40 itself extending from battery, through the winding of relay 623, the left winding and contact of relay 607, to ground at the inner left contact of relay 615. At its inner left front contact, relay 623 closes a circuit for relay 627 extending from battery, through the winding of relay 627, the inner left front contact of relay 623, to ground at the inner left front contact of relay 615.

Relay 623 at its inner right front contact 45 extends the operating circuit of message register 105 from conductor 114, over terminal 380, brush 381, conductor 329, inner right front contact of relay 623, through brush 652, and at its outer right front contact establishes a stepping circuit for magnet 657 extending from battery, through magnet 657, the outer right front contact of relay 623, interrupter 624, outer right front contact of relay 615, to ground at brush 653. Timing switch 650 now advances into position 22. As it advances through positions 11, 13, 15, 17, 19 and 21, the operating circuit for message register 105 is completed from brush 652, conductor 628, back contact of relay 337, 65 outer left contact of relay 335, through resist-

ance 339 to battery. Message register 105 is thus operated six times or three times for each five minutes of the previously conducted conversation.

To prevent the subscriber at substation 100 from interfering with the operation of the message register 105 during registration, through the operation of line relay 101, since at this time the cut-off relay 102 is deenergized, the line relay 101 is shunted down in a 75 circuit extending from battery, through resistance 340, left contact of relay 310, outer left front contact of relay 300, brush 331, terminal 332, conductor 116, thence to the inner left back contact of relay 102. It is thus 80 not possible for the subscriber to operate line relay 101 at this time.

In the meantime relay 607 in conjunction with relay 626 has completed a circuit extending from battery, winding of magnet 625 85 and its interrupter contacts, brush 601, inner right front contact of relay 627, inner right front contact of relay 607, brush 651, interrupter contacts of magnet 657, to ground at the intermediate left contact of relay 615 90 for advancing the recording switch 600 into position 21. A circuit is then prepared for operating relay 302 extending from battery, winding of relay 302, conductor 608, the outer right front contact of relay 607, terminal 95 No. 21 and brush 603, terminal No. 22 and brush 651 of timing switch 650, interrupter contacts of magnet 657, to ground at the intermediate left contact of relay 615 which circuit is completed as soon as switch 650 100 reaches position 22. Relay 302 upon energizing advances sequence switch 700 into position 18 over a circuit extending from battery, winding of magnet 700, upper left contact of cam 718, outer right front contact of relay 105 302, to ground at the upper left contact of cam 705. As soon as the sequence switch advances out of position 17, relays 609, 615, 300, 301, 310 and 311 release but relays 607, 623 and 627 remain locked to ground at brush 653 110 in position 22 of timing switch 650.

With the sequence switch 700 in position 18 a circuit is established for the down drive magnet 769 of the district selector extending from battery, through the winding of magnet 769, the upper right and lower left contacts of cam 715, to ground over the lower contacts of cam 708. When the district selector shaft reaches its normal position, brush 743 engages commutator segment 744 establishing a circuit extending from ground, at the upper right contact of cam 727, brush 743, segment 744, conductor 745, brush 606 in position 21, the outer left front contact of relay 627, interrupter contacts and winding of stepping magnet 625 to battery, advancing the recording switch 600 into position 22. A circuit is now established for advancing the timing switch 650 into normal position 125 extending from battery, winding of magnet 130

657, brush 603 in position 22, brush 651 in position 22, interrupter contacts of magnet 657, brush 606 in position 22, conductor 745, segment 744 and brush 743, to ground at the 5 upper right contact of cam 727.

As soon as switch 650 leaves position 22 the locking circuits of relays 607, 623 and 627 are opened at brush 653 and these relays release. Relay 627 upon releasing closes a 10 circuit for advancing the recording switch 600 to normal extending from battery, winding and interrupter contacts of magnet 625, the outer left back contact of relay 627, brush 601 in position 22, to ground at the inner 15 right back contact of relay 609. With the recording switch in normal position, the ground on conductor 745 is extended over brush 606 in its normal or No. 1 position, conductor 746, the lower right contact of cam 717, to 20 battery through the sequence switch magnet 700. The line finder is restored in the well known manner.

The foregoing description assumes that when the timing switch 650 advances to a position complementary to that taken by the recording switch 600, that it is arrested before reaching position 22. Should it advance, however, to position 22 and need to hunt further, for example, to assume a position complementary to position 10 of switch 600, the latter switch being assumed in a position for charging for a fifteen minute conversation, then switch 650 will continue advancing to position 22 where a circuit will be established 35 for magnet 657 extending from battery, winding of magnet 657, right back contact of relay 627, brush 603 in position 10, brush 651 in position 22, interrupter contacts of magnet 657, to ground at the intermediate left contacts of relay 615, advancing switch 650 into position 1. Switch 650 is then advanced to position 4 which position is complementary to position 10 of recording switch 600 in the manner previously described.

45 In passing through position 1 relay 627 is operated from battery, through the inner right contact of relay 615, to ground over the No. 1 terminal and brush 653 of the timing switch. If the switch 650 fails to stop, 50 not finding a definite position marked by brush 604 of the recording switch, it will advance into position 22 where the circuit previously traced for advancing it to position 1 will be opened at the outer right back contact of relay 627. Since the timing switch has not properly set itself, relay 623 has not energized and therefore a circuit is closed from ground at the upper left contact of cam 705, the outer right back contact of relay 602, the outer left back contact of relay 714, the right contact of cam 713, the outer left back contact of relay 623 to the selector time alarm circuit thereby causing an alarm to be given after a predetermined interval. 60

65 If the conversation time is extended beyond

the maximum recording capacity of the charging circuit of Fig. 6 which may be 50 minutes for a call into zones requiring but one charge for each unit period of conversation, 25 minutes for a call into a more remote zone requiring two charges for each unit period of conversation, or 15 minutes for a call into most remote zones requiring three charges per unit period of conversation, the switch 600 will stop in position 11 and the timing switch 650 will continue timing and conversation will proceed without further charge.

Charge calls initiated by substation 150.

Had the party at substation 150 initiated the call, the circuits would have functioned in the manner above described, except that when relay 308 tested, with the sequence switch 700 in positions $10\frac{3}{4}$ to $11\frac{1}{4}$, no ground would have been found and relays 308, and 310 would not have operated and after the release of relays 306, 309 and 722, sequence switch 700 would advance to position 17. Under this condition, as sequence switch 700 enters positions $16\frac{3}{4}$ to 17 the locking circuit of relay 317 is extended from battery, through the upper winding of relay 317, the lower left contact of cam 742, the outer right front contact of relay 311, the middle right back contact of relay 310, to battery through the left winding of relay 301. The cut-off relay 102 is not released since relay 300 is not operated. Relay 301 operates, in turn operating relay 615 to start charging operations. From this point, the charging takes place as previously described except that the charging circuit extends from ground, through message register 106 assigned to the substation 150, the right front contact of relay 102, the inner right back contact of relay 101, conductor 114, terminal 380, brush 381, conductor 329, the inner right front contact of relay 623, brush 652, conductor 628, the back contact of relay 337, the outer left front contact of relay 335, resistance 339, to battery.

Charge calls to other zones of exchange.

In the foregoing discussion it has been assumed that the connection was established to a remote zone of the exchange area requiring three charges per unit period of conversation. If the connection were established to a less remote zone, then the relay 611 would be operated and locked as previously described, but the sequence switch 700 of the district selector would be set into position 13 for talking rather than into position 14. Under these conditions when the timing switch 650 passes through position 2 during each of its cycles, the path previously traced for advancing the recording switch 600, extending from ground on brush 656 in position 2, the outer left front contact of relay 130

609, conductor 617, the upper contacts of cam 719, conductor 616, the inner left front contact of relay 609, brush 605 and conductor 614, to battery through the magnet 625, 5 will be open at cam 719 and the recording switch will not advance. As switch 650 passes through positions 4 and 6 during each of its cycles, however, the recording switch will advance two steps as previously described. Thus, the recording switch 10 650 is advanced only two steps during each cycle of the timing switch and only two charges will be registered on the calling subscriber's message register for each five minutes of conversation.

For still nearer zones of the exchange area, the relay 611 is not operated and the sequence switch of the district is set into position 14. When, therefore, the timing switch 650 passes 20 through position 2 during each of its cycles, the recording switch is advanced one step over the circuit previously traced through the contacts of cam 719. Since relay 611 is not operated, however, the stepping path for 25 switch magnet 625 previously traced over the right contact of relay 611 in positions 4 and 6 of brush 656 is not closed. Thus, the recording switch 650 is advanced only one step during each cycle of the timing switch and only 30 one charge is registered on the message register of the calling line for each five minutes of conversation.

No charge call.

35 It may be desirable to give free service to subscribers when they call into certain zones of the exchange area. For such calls, the district sequence switch 700 is set into position 13 for talking and relay 611 is not operated. 40 Under this condition, the advance of the timing switch during its first cycle will operate relay 335 and lock it as before but the timing switch is ineffective to advance the recording switch since all of the stepping paths to 45 magnet 625 are open either at cam 719 or at the right contact of relay 611 and therefore, the recording switch remains in its normal position 1. The timing switch, however, proceeds as before to rotate through successive 50 cycles until the conversation is terminated. As soon as the conversation ends, the district sequence switch advances into position 16 as previously described and is thence timed into position 17 under the control of relays 306, 55 309 and 722, and interrupter 723.

Since the recording switch is not advanced the circuit for operating relay 302 is now closed immediately over conductor 608, the outer right back contact of relay 607, brush 602 in position 1, conductor 703, the upper contacts of cam 702, the upper contacts of cam 710, the outer left back contact of relay 707, contacts of interrupter 735, upper contacts of cam 726, to ground at the upper right 60 contact of cam 727. Relay 302 upon energiz-

ing advances the district sequence switch into position 18 as before described where the district and line finder switches restore as hereinbefore described. Relay 615 does not energize 70 since its circuit is not closed at brush 602 of the recording switch. When the sequence switch 700 advances out of position 17, the circuit of relay 609 is opened and with relay 609 deenergized the timing switch is advanced into position 22 over a circuit extending from battery, winding of magnet 657, inner right back contact of relay 607, brush 651, interrupter contacts of magnet 657, brush 601 and normal terminal, to ground at the inner right back contact of relay 609. In position 75 22 a circuit is closed for advancing switch 650 to normal extending from battery, winding of magnet 657, brush 603 and normal terminal of switch 600, terminal 22 and brush 651 of switch 650, interrupter contacts of magnet 80 657, brush 601 and normal terminal, to ground at the inner right back contact of relay 609. The restoration of other apparatus employed 85 in the connection proceeds from this point as previously described. Since at no time was relay 623 operated, the charging path to the subscriber's message register was not closed and no charge was made.

What is claimed is:

1. In a telephone exchange system, a calling line, a called line, means for extending said calling line to said called line, a call charging device for said calling line, means for measuring the number of unit periods of conversation elapsing from the time the called subscriber responds until the calling subscriber hangs up, a recording means operative by said last means, a circuit for operating said charging device, and means controlled by said measuring means to close said circuit a number of times in accordance with the record set up on said recording means.

2. In a telephone exchange system, a calling line, called lines of different classes, means for extending said calling line to said called lines, a charging device for said calling line, a recording means, means for advancing said recording means in accordance with the number of unit periods of conversation elapsing from the time the called subscriber responds until the calling subscriber hangs up and in accordance with the class of the called line, and means operative after the calling subscriber hangs up to operate said charging device a varying number of times for each unit period recorded by said recording means in accordance with the class of the called line.

3. In a telephone exchange system, a calling line, called lines of different classes, means for extending said calling line to said called lines, a charging device for said calling line, means for measuring the number of unit periods of conversation elapsing from the time the called subscriber responds until 125 130

the calling subscriber hangs up, a recording means operated by said last means in accordance with the class of the called line, and means operative after the calling subscriber hangs up to operate said charging device in accordance with the record set up on said recording means.

4. In a telephone exchange system, a calling line, called lines of different classes, means for extending said calling line to said called line, a call charging device for said calling line, a timing switch, means operative upon the response of the called subscriber and until the calling subscriber hangs up for advancing said switch through a plurality of cycles to measure unit periods of conversation, a recording switch, means for advancing said recording switch during each cycle of said timing switch a number of steps depending on the class of the called line, and means effective after the calling subscriber hangs up for operating said charging device in accordance with the record set up on said recording switch.

25 5. In a telephone exchange system, a calling line, called lines of different classes, selector switches for extending the calling line to said called lines, means for selectively operating said switches, means associated with one of said switches for altering circuits thereof in accordance with the class of the called line, a charging device for the calling line, a timing switch, means operative upon the response of the called subscriber and until the calling subscriber hangs up for advancing said switch through a plurality of cycles to measure unit periods of conversation, a recording switch, means for variably advancing said recording switch during each cycle of said timing switch in accordance with the setting of said altering means, and means effective after the calling subscriber hangs up for operating said charging device in accordance with the record set up on said recording switch.

6. In a telephone exchange system, a calling line, called lines of different classes, selector switches for extending the calling line to said called lines, a register sender, means for variably setting the registers of said sender, means controlled in accordance with the setting of said registers for selectively operating said switches, means associated with one of said switches for altering circuits thereof in accordance with the class of the called line, a charging device for the calling line, a timing switch, means operative upon the response of the called subscriber and until the calling subscriber hangs up for advancing said switch through a plurality of cycles to measure unit periods of conversation, a recording switch, means for variably advancing said recording switch during each cycle of said timing switch in accordance with the setting of said altering means and

the setting of said registers, and means effective after the calling subscriber hangs up for operating said charging device in accordance with the record set up on said recording switch.

7. In a telephone exchange system, a calling line, called lines of different classes, selector switches for extending the calling line to said called lines, a register sender, means for variably setting the registers of said sender, means controlled in accordance with the setting of said registers for selectively operating said switches, means associated with one of said switches for altering circuits thereof in accordance with the class of the called line, a charging device for the calling line, a timing switch, a relay associated with said timing switch and operative if said registers have registered the number of a called line of a particular class, means operative upon the response of the called subscriber and until the calling subscriber hangs up for advancing said switch through a plurality of cycles to measure unit periods of conversation, a recording switch, means for variably advancing said recording switch during each cycle of said timing switch in accordance with the setting of said altering means and the condition of said relay, and means effective after the calling subscriber hangs up for operating said charging device in accordance with the record set up on said recording switch.

8. In a telephone exchange system, a calling line, called lines of different classes, selector switches for extending the calling line to said called lines, means for selectively operating said switches, a charging device for the calling line, a timing switch, means operative upon the response of the called subscriber and until the calling subscriber hangs up for advancing said switch through a plurality of cycles to measure unit periods of conversation, a recording switch, means for variably advancing said recording switch during each cycle of said timing switch in accordance with the class of the called line, means to prevent the advance of said recording switch if the called line is of a particular class, and means effective after the calling subscriber hangs up for operating said charging device in accordance with the record set up on said recording switch whereby calls to certain lines are charged on an elapsed time basis and calls to other lines are not charged.

9. In a telephone exchange system, a calling line, a called line, means for extending said calling line to said called line, a call charging device for said calling line, a timing switch, means operative upon the response of the called subscriber and until the calling subscriber hangs up for advancing said switch through a plurality of cycles to measure unit periods of conversation, a recording

switch, means for advancing said recording switch during each cycle of said timing switch, means operative after the called subscriber hangs up for further advancing said timing switch, and means controlled by said timing switch in its further advance to operate said charging device in accordance with the record set up on said recording switch.

10. In a telephone exchange system, a calling line, a plurality of called lines of different classes, means for extending said calling line to said called lines, a call charging device for said calling line, a timing switch, means operative upon the response of the called subscriber and until the calling subscriber hangs up for advancing said switch through a plurality of cycles to measure unit periods of conversation, a recording switch, means for advancing said recording switch during each 15 cycle of said timing switch a number of steps depending on the class of the called line, means operative after the called subscriber hangs up for further advancing said timing switch, and means controlled by said timing switch during its further advance to operate said charging device in accordance with the record set up on said recording switch.

11. In a telephone exchange system, a calling line, a called line, means for extending the calling line to said called line, a call charging device for said calling line, a timing switch, a recording switch, means operative upon the response of the called subscriber to start said timing switch, means for continuing the advance of said timing switch through successive cycles until the calling subscriber hangs up, each cycle of said timing switch measuring a predetermined conversational period, means controlled by said timing switch during each cycle for advancing said recording switch, means operated when the calling subscriber hangs up to advance said timing switch to a position complementary to that then occupied by said recording switch, means for then advancing said timing switch to normal and a circuit controlled by said timing switch in its advance to normal for operating said charging device.

12. In a telephone exchange system, a calling line, a plurality of called lines of different classes, means for extending said calling line to said called lines, a call charging device for said calling line, a timing switch, a recording switch, means operative upon the response of the called subscriber to start said timing switch, means for continuing the advance of said timing switch through successive cycles until the calling subscriber hangs up, each cycle of said timing switch measuring a predetermined conversational period, means controlled by said timing switch during each cycle for advancing said recording switch a varying number of steps depending on the class of the called line, means opera-

tive when the calling subscriber hangs up to advance said timing switch to a position complementary to that then occupied by said recording switch, means for then advancing said timing switch to normal, and a circuit controlled by said timing switch in its advance to normal for operating said charging device.

13. In a telephone exchange system, a calling line, a called line, means for extending the calling line to said called line, a call charging device for said calling line, means operative after the calling subscriber hangs up for operating said charging device if the call has been successful, and means for rendering the calling line substation ineffective during the operation of said charging device whereby the call charging may not be nullified by the calling subscriber.

14. In a telephone exchange system, a calling line, a line relay therefor, a called line, means for extending the calling line to said called line, a call charging device for said calling line, means operative after the calling subscriber hangs up for operating said charging device if the call has been successful, and means for shunting the line relay of said calling line during the operation of said charging device whereby the call charging may not be nullified by the initiation of a new call by the calling subscriber.

15. In a telephone exchange system, a calling line, a line relay therefor, a called line, means for extending the calling line to said called line, a call charging device for said calling line, means operative after the calling subscriber hangs up for operating said charging device if the call has been successful, and means for rendering the line relay of said calling line ineffective during the operation of said charging device whereby the call charging may not be nullified by the initiation of a new call by the calling subscriber.

16. In a telephone exchange system, a calling line, a line relay, a cut-off relay and a call charging device therefor, a circuit for said charging device extending through back contacts of said relays, a called line, means for extending the calling line to said called line, means operative after the calling subscriber hangs up for closing the circuit of said charging device if the call has been successful, and means for shunting the line relay of said calling line during the operation of said charging device whereby the circuit of said charging device may not be opened by the initiation of a new call by the calling subscriber.

In witness whereof, we hereunto subscribe our names this 17th day of October, A. D. 1927.

LEWIS H. JOHNSON.
ALFRED E. HAGUE.
